UNITED STATES PATENT OFFICE.

EDWARD TODD, OF NEW YORK, N. Y.

DESIGN FOR A PENCIL-CASE OR SIMILAR ARTICLE.

SPECIFICATION forming part of Design No. 15,060, dated June 10, 1884.

Application filed April 12, 1884. Term of patent 7 years.

To all whom it may concern:

Be it known that I, EDWARD TODD, (assignor to EDWARD TODD & Co.,) a citizen of the United States, residing at New York, in the county of New York and State of New York, have invented and produced a new and original Design for Pencils, Pen and Pencil Cases, and Toothpicks, of which the following is a specification, reference being had therein to the accompanying drawing.

My invention, relating to pencil-cases or similar articles, is fully shown in the drawing accompanying this specification; and it consists in the design of a case, *a*, conventionally re-

presenting a wire spring or coil throughout its entire length.

What I claim as new, and desire to secure by Letters Patent, is—

A design for a pencil-case or similar article, consisting of a conventional representation of a spiral spring or coil throughout its entire length, as described and shown.

In testimony whereof I affix my signature in presence of two witnesses.

EDWARD TODD.

Witnesses:

D. W. HUTCHINSON,
GEO. B. FLYNN.
